[57] CLAIM

The ornamental design for a combined scorekeeper and holder for golf accessories, as shown and described.

DESCRIPTION

FIG. 1 is a perspective view of a combined scorekeeper and holder for golf accessories showing my new design; FIG. 2 is a front elevation thereof, the rear being similar except that the ball slot opening would be replaced by a solid back;

FIG. 3 is a top plan view;

FIG. 4 is a side view looking from the right hand side of the view in FIG. 3; and,

FIG. 5 is a bottom plan view thereof.

The broken lines shown indicate environment only and form no part of the design.
